Jedediah Richards June
Letter Patent

The Article referred to in these Letter Patent and mentioned
in the same containing a description of the Article and its Construction
with the Elements of the machine, consists of a machine constructed
with Wrought Blanks, does, give all kinds of Wrought work, tools
these frames and all kinds of small ornaments with.

The first machine is, for a small Wrought work, I have a frame with
you will see, first two iron uprights with one girl to make from the floor
bent to the back with iron counterbells. The machine is then put together
and, is put with two counterbells, that is to say, one
in the middle. I have two middle bushes to support the upper part, on
the girls, I have a drum, two feet diameter. In the top of the machine
I have one man, I have two men, that stand horizontal, these places
are on a staff that stand perpendicular to the staff, the staff
is wanted to be thick with a back between them. Having ^{and} two
staffs to one thickness, required, for the work, by pulling between the
two, opposite ends, these two frames are fast that stand
back of the man. At the bottom of the man staff I have a staff
inches to the first with a cross, so that the man can be in
it and stand, as may require, below the man on the lower staff,
I have taken, that the bell may sound to drive the man, this
bell is in, one bush each, that are to be made in diameter, these which
hang on a frame, that sides back and forward to toggle and loose
the cord. These which, have bells, from perpendicular to a horizontal
position, this bell, is put, given these about to the man down
I have one, so that stand perpendicular beyond the two upright
staffs. This one, set off the staff from the place, these are to drive
by a bell that goes down the accelerating wheel that hangs on a
wing frame and from the drum to this wheel, there a bell, &

when the swing is brought back by a bridle or tightrope, the lower end and gives motion to the swing to hold the step to be set off. There are two large wooden blocks that are let out & taken up to the length of the piece to be raised by means of a rod that is fastened under the head blocks by a screw at each end to take up the head blocks, & let them out as they may require. The head blocks are made of iron 16 inches long & ten inches wide & one half inch thick. The head block has a semicircular depression. There then is a piece in the head block, four inches wide, rising higher than the iron that connects the two parts of the head block, on the right hand head block there is a slide, on the one side slide & have a handle that is fastened to head to the second head block, the piece then rising when the pin is wound in raising the handle it is lowered on the inner edge of the head blocks. There are grommets lay on the piece at each end the head blocks are on ribbons, these ribbons lie on the top timber of the frame.

The second machine is for planing, it is a wooden frame, the part one inches wide. The first three parts are made high. There are two parts, first long & second short wide and short, that are arranged all together with iron bolts. There are two iron bars, the one piece in the first part in the second the bottom. The wheel part the main wheel is two feet four inches diameter with iron iron rank & shaft. The shaft is in the form of a 'T' with two square sections at the end of the 'T' shaft, side to side. The slide is held in the counter shaft given being the two square, the wheel is hung on the two left hand parts, one on either at the end of the slide. The platform is attached to a slide that is on the back part of the machine. This slide is attached to a beam with a tongue & groove that holds the slide steady. This slide is horizontal with the counter shafts having shafts of iron at the end of the slide. The slide runs on these shafts with two others, each shaft one eight inches and the other four inches. These are bolts secured to these & attached to the slide to increase grip & are used to tighten the bolts on the beam when these are bolts fastened that hold to the frame part.

The frame jacks, is made of three pieces of wood, the upright pieces are seven inches long, the horizontal piece is ten inches long. The two upright pieces have a grommet in the ends to fit ways taken therefrom. They are lined with metal to prevent their wear. This jacks runs between the ways. The ways are attached to a beam. This beam is seven inches apart at each end. That passes down thro' the bed pieces, at each end of the way beam there is an iron bolt twenty inches long with a screw & nut at the bottom. The nut is fastened to the bed. The bolt has a collar that is attached to the way beam. There is a handle on the top of the bolt where the bolt is turned, it turns, and raises the frame. The ways are fastened to four upright pieces. These pieces are set in the way beam. On the bottom of these pieces one of the ways is fastened. The upper way is fastened to the top of these pieces with screws, so that it can be let down on the track to lighten it on the bottom of the jacks. The riding tool and frame are provided with two ways on the bed pieces. & have a carriage pole, feet long & two feet wide to lay the stuff out to be fastened, raised back to ride, raised, & a nail and pinion on each end of a shaft. The shaft is as long as the carriage & this to take the carriage with a weight of 1000 lbs. the shaft is in the carriage & fastened in the carriage. This way which is worked to a hand bolt is attached to the back side of the carriage and pinion moving the carriage. The two ways riding, and which gives the frame motion.

The third machine is for setting and lowering. This machine is a frame with four posts, two feet ten inches long with four girts. The makers from the bottom of the posts are secured with iron bolts on these girts. I have a drum two feet diameter that carries the ways on the top of the posts. I have two plates, seven feet long and two beams, five feet long between the beams. I have four crooked irons to give the timber no leaning. I have a frame three feet long, one foot eight inches wide, twelve inches high. This frame holds the timber on to tension. I have a post, five feet long bolted to the frame. The end of the top frame is connected with

this post. on this post & have two pieces of iron bar inches long with the ends turned out to receive a screw that goes thro the post head. These pieces head hold the shoulders down. There may have a notch in the middle and a bolt that goes through the post. a screw nail on the outside of the post. by these means the wheel will stand and lowered moved back and forward. the pins to turn my saws between these bars. first the rear bars one over the other eight or ten inches beyond them saws I have two horizontal bars on one shaft that slide the lesson is prepared as the lesson is thick. the shaft at the bottom stands on a single bar. & is fitted in a slot and grove that it be moved off and on to come down with the shoulders down. the upper end of this shaft is fitted with a cap that stands on a short post. this cap has a notch and a slot in it that these, can now be moved back and forward & fastened to any place. these may be drawn back from the main drum that goes, over the wheel, and being the band from a perpendicular to a horizontal course. these wheels are made in the diameter. these may hang on a frame that they may be adjusted to tighten and loosen the band. the band is connected to the rear shaft below the saws. - the shoulders down are drawn back & placed under the platform when the shaft is turned. & a wheel drawn beyond the saw shaft. this wheel is six inches diameter with two bolts to carry the saws at the other end of the shaft. I have a wheel four inches diameter. a band leading from this wheel to the main drum. the shaft at this end is turned & turned to stop the saws. The saw that is for cutting is on the right hand side of the frame in full motion by an accelerating wheel. this wheel turns on a wire that is moved backwards and forwards for a loose wheel tightening and loosening a band connected with this wheel & the main drum which stops the wire giving it motion. the object of this wire is to stop the saw and give it motion. the front machine is for mortising. this machine has two parts. one near the left part of the wire, and from under the

vention makes below this upper part is another part the same length & size those parts are fastened to the posts by tenons and screw bolts. Thus, we hold two front posts, these hold the arched gate on the inside of the posts, there are two iron ways that that iron mount fastened at each end with eyes that go through the posts, the gate is made with three pieces of timber one slanting downward and two horizontal above and of the horizontal pieces is a hollow groove that sits on them mounting, these iron-rod pieces are eight inches long three inches wide & two inches thick. The middle beam is four inches wide two inches thick and six inches long. They are fastened with two iron bolts with eyes at the bottom where the postman is hung these bolts go out through the middle piece of the gate on the top of the gate there are two iron nuts at the upper end of the bolts on the bottom piece of the gate. There are two pine plates fourteen inches long each with a half inch and three eighths of an inch thick bolted to the bottom of each side of the gate, the arched posts are fitted on these blocks in a manner as long as the distance of one end of one inch & square meeting in this projection that the arched posts fit with two iron nuts on each side that blocks that are secured against the arched posts the back side of the plates are two projections that are to go on each side of the plate to keep the blocks steady. On the thin part of the arched blocks there is a notch and a concave that cuts the pine & that pine blocks can be moved backwards and forward to make any size such. On these blocks, & since the smaller blocks for supporting the middle work, behind the plate there are single blocks that receive the end of the stairs. The last piece that the stuff lies on to make is a piece of timber five inches square, four feet long it stands on two iron, that the last piece may be turned and raised to suit any height, of stuff this last piece lies in front of the posts. This last piece has, moving steps, that will move to receive any length of stuff required. The piece is held between them all the stuff is worked from the end, between the end steps. I have middle steps when the piece is moved from one step to the other by working against the middle step with

piece to be, or sliced it more, back out of the way. it is brought forward by a spring. the tiles are laid over of the bed piece to mortise by this bed piece and the mortises are made in the piece in one handling back of the bed piece and step to gauge the ends of the tiles from the gate determined at time the first time. it is attached to a crank by an with the index screw. the work wheel is here in the chain she & hangs on a frame within six inches of the floor. This gives the foot, in journal to it, feel in motion from the main beam it is stopped and set in motion by a handle with the foot.

The next machine is for breaking rough stalling & making pins. for this machine I have four posts ten feet ten inches high, four posts ten inches from the bottom, on these posts I place a beam two feet diameter, on the top of the post I have two plates, one just back of the frame. I have two beams, four feet long between them, I have four tail timbers to hang the posts to on the right side of the frame & have a rough stalling saw on the back end of the frame. I have a saw cutting timber to the length. This saw is stopped and set in motion by a spring & an oscillating arm & is managed by the foot. & is made to cut the stuff to even given length. I have a table with a step at one end this table is fastened with a screw. I have a block to hold the stuff against that is square with the saw. that goes over the saw with a gap in the block for the saw to pass, this block the straight side of the stuff is held against this block is guided by two other screws from the under side running each side of timber, that is the step timbers of the frame.

The pin machine is made with three pieces of timber three by six inches the two posts twenty inches long, the last piece sixteen inches long on the inner side of the posts I have a yoke the yoke hangs in that on one the piece that drives the pin from the yoke & it turns a pinion that is attached to a crank one index screw on the crank shaft I have a wheel twenty inches diameter that carries a bell that sets the machine in motion. when the pin is made there

a die made the size of the pin over this die I have a gauge plate that holds the pin before it is cut above the gauge plate I have an iron box that the pin falls in when the pin is in this box there is a slide that stores the pin & holds it until the die is struck at the slide is open and just sets the gauge plate when the die is down the pin falls thro' a hopper by the side of the slide. The improvement is different from A. since is as follows. The first machine is all my invention or improvement. The pinning machine differs from this in this. The frame is longer & the main wheel is hung on the left end of the frame by having two rotating shafts. The shafts are arranged with with the number of the cards to the back side and the main wheel is fast to one of the pins and the front wheel when the plane is hung the main wheel runs and turns the frame. Starting at A. is different it differs in this frame and wheel use the steel stock and the pieces the last piece is made with a hole that any piece of timber is inserted before it is cut away without breaking the wood.

Another A. B. C. is different in the tenoning first. The wood pieces first made then the pieces to be tenoned passed to the setting box where the pieces is finished. The setting box are arranged in a line from the main frame that pieces are tenoned from a perpendicular to a horizontal manner all the other same except these that under the guidance of the tenon are put in motion & stopped by a ring of iron. The pin machine is to B. is my improvement.
